ADJUSTABLE SURE GRIP HANDLE

Filed June 30, 1923

UNITED STATES PATENT OFFICE.

CHARLES R. CUSTIS, OF HARRISON, NEW JERSEY.

ADJUSTABLE SURE-GRIP HANDLE.

Application filed June 30, 1923. Serial No. 648,828.

To all whom it may concern:

Be it known that I, CHARLES R. CUSTIS, a citizen of the United States, residing at Harrison, in the county of Hudson and State of New Jersey, have invented certain new and useful Improvements in Adjustable Sure-Grip Handles; and I do hereby declare the following to be a full, clear, and exact description of the invention, such as will enable others skilled in the art to which it appertains to make and use the same.

This invention relates to a handle.

It is aimed to provide a handle of general adaptation but particularly one which may be applied to brake valve operating mechanism or the like so as to insure safe and more expeditious operation thereof.

Another object is to provide a construction of handle in which the parts are adjustable so as to accommodate attachment to different sizes and kinds of operating means or the like, one in which a sure and tight grip connection is attained by turning of a part of the handle and one in which lost motion due to wear of the parts may be taken up and minimized.

Another object is to provide a construction in which the handle proper consists of three parts, two of which are adjustable through movement of the third part.

Various additional objects and advantages will become apparent or be pointed out from a consideration of the description following taken in connection with accompanying drawings illustrating an operative embodiment.

In said drawings:—

Figure 1 is a perspective view of the tool with the handle detached;

Figure 2 is a plan view of the tool but showing the handle in section;

Figure 3 is a perspective view of one of the jaws of the tool;

Figure 4 is a perspective view of the other jaw of the tool;

Figure 5 is a cross section on the line 5—5 of Figure 2 passing through the spring;

Figure 6 is a cross section on the line 6—6 of Figure 2 passing through the screw, and

Figure 7 is a perspective view of a modified form of the tool.

Like reference characters designate like or similar parts in the different views.

In reducing the invention to practice, separable sections A and B are provided which have jaws 10 at one end collectively forming

a socket adapted to engage an article to be operated and which is received within a square or other recess 12 formed thereby. These jaws 10 are adapted for separation 60 along a line 13.

Beyond the line 13, the sections are enlarged into the conical portion 14 beyond which a screw threaded shank 15 is provided. Section B at the conical portion is separable from the section A along the planes at a right angle to each other as represented by the lines *a* and *b*. Section A at the larger end of the portion 14 has a lug 16 which is adapted to interlock with means on the part engaged and operated by the handle to hold the same in adjusted positions.

Adjacent its smaller end, the portion of jaw B at conical portion 14, is fastened to 75 the section A by a set screw 17 passing through the portion 14. Section B about the set screw 17 is somewhat loose as the opening through which the set screw passes is enlarged. Adjacent the larger end of the 80 conical portion 14, an expansive helical spring 18 is housed within the section A and in engagement with section B so as to urge the latter away from section A. The tendency of spring 18 therefore is to urge 85 the jaws 10 slightly away from each other.

A pressure sleeve 19 is provided which has a conical wall 20 adapted to engage the conical portion 14 in order to compress the sections A and B together and this sleeve includes interior screw threads at 21 which are engageable with those of the shank 15. The sleeve is thus held in place through the engagement of such screw threads. Surrounding the sleeve is a handle or grip 22, 95 fastened to the sleeve in any suitable manner and being for instance straight and of wood but which may be of any other suitable shape or material.

In use, when the sleeve 19 is loose upon sections A and B, the spring 18 separates the sections slightly at the jaws 10 whereby they may receive the part to which the handle is to be connected. Thereupon, the handle is turned so as to move inwardly and thereby cause the wall 20 to move along the portion 14 and compress the sections A and B together by the coaction with the conical portion 14. In this manner, the part engaged or gripped may be very efficiently 100 secured and a rigid connection of the handle made therewith. Should play develop be-

2
tween the handle and that portion or the parts become worn or loose, such play or looseness may be taken up by further tightening the handle. As the sleeve 19 extends over the screw 17, the latter cannot become accidentally detached. It will be noted that the section A is made in a single piece, that the section B is made in a single piece and that the sleeve 19 is made in a single piece. These sections and sleeves therefore may be readily cast or drop forged. Due to the adjustable connection of the parts, the device may be secured not only rigidly to operating mechanism but may be connected to such mechanism or any part desired, and which may vary slightly in size.

Changes may be resorted to within the spirit and scope of the invention and it is also to be understood that the handle is adapted for use broadly and not limited to the use illustrated.

As an example of a modification, the form of Figure 7 is embodied herein. In that figure, the difference resides merely in the position and relation of the jaws 10 with the remainder of the tool and also in the position and relation of the lug 16, and in this figure, such jaws are designated 10^a and the lug 16^a. Otherwise the two forms are the same.

What is claimed is:—

1. A device of the class described having sections providing gripping jaws, said sections collectively having a substantially con-

ical portion, one of the sections at said portion being substantially V-shape in cross section and the other section being correspondingly grooved to receive the same, a screw threaded shank on one of the sections beyond said conical portion and the other section, and a sleeve constituting a grip for the device screw threaded to said shank and having a substantially conical wall to engage the conical portion to compress the latter.

2. A device of the class described having sections providing gripping jaws, said sections collectively having a substantially conical portion, one of the sections at said portion being substantially V-shaped in cross section and the other section being correspondingly grooved to receive it, means loosely connecting the sections together adjacent said portion whereby one section may move radially with respect to the other section, a spring to urge separation of the jaws, a screw threaded shank on one of the sections beyond said portion and the other section, and a sleeve constituting a grip for the device screw threaded to said shank and having a substantially conical wall to engage the conical portion and compress the latter against the tension of the spring.

In testimony whereof I affix my signature in presence of two witnesses.

CHARLES R. CUSTIS.
